LOUIS G. BOSTEDO, OF LOS ANGELES, CALIFORNIA.

METHOD AND MEANS FOR PROPELLING CRAFT NAVIGATING FLUID MEDIUMS.

1,305,340.

Specification of Letters Patent. Patented June 3, 1919.

Application filed August 3, 1917. Serial No. 184,362.

To all whom it may concern:

Be it known that I, LOUIS G. BOSTEDO, a citizen of the United States, residing at Los Angeles, in the county of Los Angeles and State of California, have invented certain new and useful Improvements in Methods of and Means for Propelling Craft Navigating Fluid Mediums, of which the following is a specification.

10 This invention relates to an improved method of and means for propelling air and water craft; the broad principle of the invention being capable of useful application to the propulsion of air craft and surface 15 and sub-surface water craft.

In the present known devices for effecting the propulsion of both air and water craft, all the propeller blades can do is to bat the molecules of the air or water and receive the 20 recoil from the molecules which they strike. It is the impact of the recoiling molecules—collectively their pressure—which pushes the 25 craft forward. And a propeller blade is constrained to bat the molecules only as the transmitted and weakened effect of a piston head being batted by other molecules in a cylinder wherein they are energized by the heat of combustion.

My present invention is based upon the 30 broad principle of causing a gaseous body, the molecules of which are energized by the heat of combustion or otherwise, to expand continuously and with substantially constant pressure directly between the craft and the 35 fluid medium (air or water) through which the craft travels, without the intervention of any motor, engine or propeller blades or any other moving parts.

In its simplest and what might be termed 40 its most rudimentary form, my invention employs a tube that constitutes in effect a gas expansion chamber. This tube has a relatively small inlet for air or oxygen at its front or forward end and a relatively large 45 outlet for the products of combustion or expansion at its rear end, and to this tube, where the molecules are energized by the heat of combustion, are applied a means for introducing a jet or spray of fuel preferably 50 in liquid or vapor form to mix with the air or oxygen, and a means for initially igniting the combustible charge. When adapted for the propulsion of air craft, the ratio of the diameters of the front and rear openings is

such that, after allowing for the vaporization of the fuel sprayed into the combustion chamber and the expansion of the products of combustion by the heat, the velocity of the outflowing gases is less than the velocity of the tube through space. Because of this, 55 the gases seeking to flow out through the front inlet are overcome by the superior pressure of the atmospheric air which, considered relatively to the tube, enters it the same as in an ordinary house furnace, except 60 that in the present case the tube moves through the atmosphere, while the house furnace is stationary. Or, in lieu of the latter, a continuous current of air or oxygen may be forced into the small end of the tube 65 by means of a fan, positive blower, or air compressor, or by expansion of liquid air or oxygen by the heat of the atmosphere, or, when adapted for the propulsion of water 70 craft, by the heat of the body of water on or 75 in which the craft travels.

In the simple form above outlined, the efficiency of such a device would necessarily be somewhat limited for the reason that the volume of air which can pass through the 80 largest tube that a craft could carry would over-cool the combustion chamber and thereby cause incomplete combustion. On the other hand, if enough fuel is burned to maintain good combustion, the exhaust gases will 85 carry off too much unused heat.

To overcome the foregoing objections, I have devised a form of combustion tube wherein the air is preliminarily heated before entering the combustion chamber of the 90 tube and mingling with the fuel, and wherein the products of combustion pass from the combustion chamber directly into what I term an expansion chamber wherein they commingle with an additional volume of air 95 entering through the front of the tube, expanding the latter, the exhaust passing in a continuous stream out of the rear end of the expansion chamber. This expansion chamber is preferably of considerable length so as 100 to allow an expansion of gases within the chamber down to at least the temperature of the surrounding air.

In order to facilitate a clear understanding of the principle of my invention, and to 105 illustrate a practical embodiment thereof as applied to the propulsion of air craft, reference is made to the accompanying drawings

wherein I have illustrated in a largely diagrammatic form an apparatus by which the invention may be carried out. In these drawings I have not attempted to illustrate 5 in full detail all of such coöperating and accessory devices and parts as might be found desirable in practice and are well known to and understood by those skilled in the art of internal combustion motors and 10 the art of fluid fuel burning.

Referring to the drawings,

Figure 1 is a longitudinal section broken away between its ends through the expansion chamber and taken on the line 1—1 of 15 Fig. 2.

Figs. 2 and 3 are cross sections on the lines 2—2 and 3—3 of Fig. 1 respectively.

Fig. 4 is a detail view similar to the left hand end of Fig. 1 and illustrating the 20 application of a positive air feeding device for the combustion chamber.

Referring to the drawings, 5 designates a tube that constitutes the expansion chamber, this tube having an end wall 6 at its forward end and being open at its rear end, and of such a length as theory and experiment may determine to afford the highest efficiency. To and in advance of the forward end wall 6 are secured four coaxial 25 tubes 7, 8, 9 and 10. The tube 9 is closed at its forward end by the wall 11, and the walls thereof are lined with fire brick or similar highly refractable material as indicated. Preferably there is also applied to 30 the outer side of the end wall 11 a protecting shield 12 of heat insulating material designed to permit the end wall 11 of the furnace to remain hot and practically unaffected by the cold air striking the same. 35 The inner tube 10, which is open at its forward end, constitutes an air supply conduit and also a protective housing for an oil inlet tube 13 that terminates at its free end in a vaporizer or atomizer 14 designed to 40 spray oil directly into the interior of the tube 9 which constitutes the furnace chamber. The oil pipe 13 connects with an oil reservoir 15 in which a suitable air pressure is maintained from a compressed 45 air tank 16, the pressure being admitted and controlled by a valve 17 in the pipe 18 connecting the compressed air tank with the oil tank.

The tube 8 surrounds the furnace tube 9 50 with sufficient clearance to provide for the admission of air used to support combustion. The air flowing into and through the annular space between the tubes 8 and 9 is directed into the rear end of the inner tube 60 10 through a series of transverse ducts 19, so that the air enters the combustion chamber along with the vaporized oil through the open forward end of the inner tube 10.

In the end wall 6 of the expansion chamber are formed a series of openings 20 (Fig.

2) that are disposed between and in alternating relation with the ducts 19, and through these openings the hot products of combustion pass from the combustion chamber into the expansion chamber formed by 70 the tube 5.

The end wall 6 of the tube 5 is further formed with a series of openings 21 through which the larger body of cold air entering between the tubes 7 and 8 is permitted to 75 flow into the expansion chamber.

Suitable dampers are employed to control the amount of air flowing to the combustion and expansion chambers respectively. In the drawings I have indicated a sleeve 80 damper 21' surrounding the combustion chamber tube 9 opposite the ducts 19 and formed with holes 22 which may be brought more or less into register with the outer ends of the ducts from the operator's seat 85 by suitable connections including a link 23 (Fig. 3). Mounted on the inner face of the end wall 6 is a ring damper 24 rotatably mounted in supporting lugs 25 and formed with a series of openings 26 adapted to be 90 brought more or less into register with the holes 21, as shown in Fig. 2, said ring damper being likewise controllable from the seat of the operator through suitable connections including a link 27.

The combustion chamber is further equipped with means for initially igniting the fuel such as an ordinary spark plug indicated at 28 connected, of course, to a switch-controlled ignition circuit and generator.

From the foregoing it will be seen that inflowing cold air is not permitted to enter the combustion chamber cold, but is conducted along and surrounding it a sufficient 105 distance to insure its being well heated. It then turns inward through the ducts 19 into the central inlet tube 10, passing the atomizer and mixing with the atomized hot oil as it enters the combustion chamber or furnace. This arrangement provides for maintaining a white hot continuous fire in the furnace, whose thick refractory walls do not lose more heat than is required to heat the incoming cold air taken by the inner air tube for the furnace. As stated, the front 110 end of the furnace is shielded by the cap 12 from the direct impact of the atmosphere.

The relatively large expansion and mixing chamber 5 is made large enough to give the 120 cold air entering through the openings 21 time to mix with the hot products of combustion before the mixture discharges into the atmosphere in the rear. To avoid unnecessary waste of heat the walls of the 125 expansion chamber 5 are likewise lined throughout their forward portion with heat-insulating material indicated at 29.

The several chambers and passageways are 130 so proportioned as to attain the highest effi-

- ciency, the object being to maintain continuous perfect combustion and prevent, so far as possible, any heat from escaping without imparting its energy to gas molecules
- 5 within the tube, which in turn exert pressure against the front ends of the furnace and expansion chamber. The greatest possible net area of these ends is important; the highest possible velocity of the discharging gases is
- 10 also important. But neither of these factors can be unduly increased without unduly diminishing the other, and experiment will best determine the proper relative proportions that will yield the highest efficiency.
- 15 Furthermore, it is desirable to discharge the gases at a temperature as nearly as possible down to that of the atmosphere, this condition being controlled by the insulation and the dimensions of the expansion chamber.
- 20 It is theoretically possible to allow the discharging gases to acquire a velocity and momentum that will so rarefy them as to lower their temperature below that of the atmosphere; and in this case I propose to
- 25 pass them through a rear discharge section with much conducting surface and of good conducting material like aluminum, this being indicated at 5^a in Fig. 1. This will permit the atmosphere to supply enough
- 30 heat to restore the temperature of discharge to that of the atmosphere, thus maintaining the maximum velocity as well as efficiency.
- Since the immediate cause of propulsion is the forward impact of molecules against
- 35 the inside front ends of the furnace and expansion chamber, it follows that it is desirable to have the heat of combustion energize the gases as near these surfaces as the structural conditions will admit.
- 40 In the apparatus shown in Fig. 1 and thus far described there has been assumed no pressure upon the inflowing cold air, other than that of the entering draft due to the forward motion of the craft. There are two
- 45 practical ways by which increased air draft may be secured if found desirable. In the first case, the propulsive device shown and described may be employed as an auxiliary propeller along with a standard mechanical
- 50 propeller such as is now used, and in this case the increased speed due to the presence of the standard propeller will create a much stronger air draft, which is equivalent to the mechanical draft of a fan in accelerating the
- 55 entrance of the air. The other way is to use forced mechanical draft, such as a rotary fan or blower which I have indicated at 30 in Fig. 4, the discharge of such blower being connected directly to the front end of the
- 60 tube 8 which supplies the air for combustion. With mechanically forced draft, especially if it is of the positive air-compressor type in which the air slip is negligible, the operation can be under higher pressure and intensified.
- 65 Higher discharge velocities can be utilized,
- and the combustion and expansion chambers may be smaller in proportion to the power developed.
- I claim:
1. A method of effecting propulsion of a craft or vehicle, which consists in continuously burning fuel within a combination furnace and expansion chamber open at its rear or trailing end and of such form and dimensions that the products of combustion expand laterally as they flow from the furnace to the exhaust, lowering their temperature to approximately that of the enveloping medium, thereby applying the latent energy of the fuel to maintaining the working propulsive pressure of the said products of combustion during their expansion, which pressure continuously urges the craft or vehicle and the exhaust products of combustion in opposite directions.
2. A method of effecting propulsion of a craft or vehicle, which consists in continuously burning fuel in a heat-insulated furnace carried by the craft or vehicle, conducting the products of combustion directly from the furnace into an expansion chamber and thereby reducing their temperature to approximately that of the enveloping medium while maintaining their pressure above that of the enveloping medium, and discharging said products directly from the expansion chamber into the enveloping medium, whereby substantially all of the latent energy of the fuel is applied to maintain the working propulsive pressure of the products of combustion at the maximum volume of discharge into the enveloping medium.
3. A method of effecting propulsion of a craft or vehicle, which consists in continuously burning fuel in a furnace carried by the craft or vehicle and having an expansion chamber open at its rear, and, by means of the respective dimensions of the furnace and expansion chamber, conditioning the expansion of the products of combustion in two stages, namely, first, the furnace stage in which the expansion is limited to an extent at which the temperature will be the most favorable for perfect combustion, and, second, the expansion-chamber stage in which the expansion is sufficient to lower the temperature and condition the velocity to the point of most efficient reaction; thereby applying the fuel energy to maintaining the working pressure of the products of combustion throughout their expansion.
4. A method of effecting propulsion of a craft or vehicle, which consists in maintaining a continuous flow of fuel and a combustion supporting fluid into a furnace carried by the said craft or vehicle, and a continuous flow of the products of their combustion from the furnace into and through an expansion chamber, and thence discharging

- into the enveloping medium at a working pressure substantially constant, but with the entrance pressure kept sufficiently above the exhaust pressure to maintain the required supply of fuel and combustion-supporting fluid; the expansion of the fluids occurring in two stages, namely, first, in the furnace by combustion to a temperature favorable to perfect combustion at the conditioned working pressure, and, second, in the expansion chamber to the volume which will bring the temperature to approximately that of the enveloping medium at the conditioned discharge pressure; thereby converting the maximum portion of the fuel energy into the increased molecular energy of the products of combustion required to maintain their working pressure throughout their expansion.
5. A method of effecting propulsion of a craft or vehicle, which consists in maintaining by continuous combustion in a combination furnace and expansion chamber carried by said craft or vehicle the working propulsion pressure of a continuous stream of fluids which are kept flowing through said furnace and expansion chamber, said fluids comprising fuel and air or oxygen when they enter the furnace, and the products of their combustion plus additional air or oxygen when they enter the expansion chamber; the relative dimensions of the entrance, exit, furnace and expansion chamber being such that the expansion of the stream of fluid in the furnace is just sufficient to condition the temperature of perfect combustion, and in the expansion chamber the temperature is lowered and the velocity conditioned to the point of most efficient reaction; thus utilizing the utmost portion of the fuel energy in maintaining the maximum volume of the motive fluid at the working propulsion pressure.
6. A propulsive device for craft navigating a fluid medium, consisting of a propulsion-tube rigidly attached to the craft and closed at its forward end and open at its rear or trailing end, and means for effecting by internal combustion a continuous and substantially uniform expansion of an expansible fluid within said propulsion-tube.
7. A propulsive device for craft navigating a fluid medium, consisting of a propulsion-tube rigidly attached to the craft and open at its rear or trailing end, means for continuously supplying a combustible fluid to said tube, and means for initially igniting said combustible fluid in said tube.
8. A propulsive device for craft navigating a fluid medium, consisting of a propulsion-tube rigidly attached to the craft and open at its rear or trailing end, means for continuously supplying fuel and a combustion-supporting agent to said tube, and means for initially igniting the fuel in said tube.
9. A propulsive device for craft navigating a fluid medium, consisting of a propulsion-tube rigidly attached to the craft and open at its rear or trailing end, means for continuously supplying a combustible fluid to said tube, and means for initially igniting said combustible fluid in said tube, said tube being of sufficient size to permit the products of combustion to expand down to substantially the temperature of the surrounding fluid medium before being discharged into the latter.
10. A propulsive device for air craft, consisting of a propulsion-tube rigid with the craft and open at its rear or trailing end, the forward portion of said tube constituting a combustion chamber or furnace and the rear portion being of larger diameter and constituting an expansion chamber communicating with said combustion chamber, means for supplying a combustible fluid to said combustion chamber, means for initially igniting said combustible fluid, and means for admitting air to said expansion chamber to mingle with and be expanded by the products of combustion from said combustion chamber.
11. A propulsive device for air craft, consisting of a propulsion-tube rigid with the craft and open at its rear or trailing end, the forward portion of said tube constituting a combustion chamber or furnace and the rear portion being of larger diameter and constituting an expansion chamber communicating with said combustion chamber, means for supplying a combustible fluid to said combustion chamber, means for initially igniting said combustible fluid, and means for admitting air to said expansion chamber to mingle with and be expanded by the products of combustion from said combustion chamber, said expansion chamber being of sufficient size to permit the gases therein to expand down to substantially the temperature of the surrounding atmosphere before being discharged into the latter.
12. A propulsive device for air craft, consisting of a propulsion-tube rigid with the craft and closed at its forward end and open at its rear or trailing end, the forward portion of said tube constituting a combustion chamber or furnace and the rear portion being of larger diameter and constituting an expansion chamber communicating at its forward end with the rear end of said combustion chamber, a tube surrounding said combustion chamber and forming with the latter an annular passage for the intake and preliminary heating of air to support combustion, an air conduit leading from said annular passage to the interior of said combustion chamber through the rear end

of the latter, means for supplying fuel to the combustion chamber, means for initially igniting the fuel, and means for admitting air to said expansion chamber to commingle with and be expanded by the products of combustion therein.

13. A propulsive device for air craft, consisting of a propulsion-tube rigid with the craft and closed at its forward end and open at its rear or trailing end, the forward portion of said tube constituting a combustion chamber or furnace and the rear portion being of larger diameter and constituting an expansion chamber communicating at its forward end with the rear end of said combustion chamber, an air inlet tube extending inwardly of the combustion chamber from the rear end of the latter, a tube surrounding said combustion chamber and forming with the latter an annular passage for the intake and preliminary heating of air to support combustion, an air conduit leading from said annular passage to said air inlet tube, an outer tube surrounding the second-named tube and forming therewith an annular passage in communication with said expansion chamber and serving to admit atmospheric air to the latter, means for supplying fuel to the combustion chamber, and means for initially igniting the fuel in the combustion chamber.

14. A propulsive device for air craft, consisting of a propulsion-tube rigid with the craft and closed at its forward end and open at its rear or trailing end, the forward portion of said tube constituting a combustion chamber or furnace and the rear portion being of larger diameter and constituting an expansion chamber communicating at its forward end with the rear end of said combustion chamber, an air inlet tube extending inwardly of the combustion chamber from the rear end of the latter, a tube surrounding said combustion chamber and forming with the latter an annular passage for the intake and preliminary heating of air to support combustion, an air conduit leading from said annular passage to said air inlet tube, an outer tube surrounding said second-named tube and forming therewith an annular passage in communication with said expansion chamber and serving to admit atmospheric air to the latter, all of said tubes being arranged coaxially with each other and with said combustion and expansion chamber, means for supplying fuel within said air inlet tube, means for controlling the amounts of air admitted to said combustion and expansion chambers, and means for initially igniting the fuel in the combustion chamber.

LOUIS G. BOSTEDO.
